HARRY J. WIEDERECHT, OF NEW PHILADELPHIA, OHIO.

STEAM-TRAP.

1,046,131.

Specification of Letters Patent.

Patented Dec. 3, 1912.

Application filed May 27, 1911. Serial No. 629,915.

To all whom it may concern:

Be it known that I, HARRY J. WIEDERECHT, a citizen of the United States of America, and resident of New Philadelphia, county 5 of Tuscarawas, and State of Ohio, have invented certain new and useful Improvements in Steam-Traps, of which the following is a specification.

This invention relates broadly to steam 10 traps, and specifically to a trap having novel and improved means whereby the outlet to the waste-pipe or atmosphere is automatically controlled.

The primary object of the invention is to 15 provide a steam trap which is simple in its construction, which is positive and reliable in its operation, and which has but few parts likely to become out of order through wear and corrosion.

20 A further object within the contemplation of this invention is to provide a device of the character mentioned wherein the water passages are of such size as not unnecessarily to restrict or retard the flow of water 25 therethrough.

Further objects will be in part obvious and in part pointed out hereinafter.

The invention accordingly consists in the 30 features of construction, combinations of elements and arrangement of parts which will be exemplified in the construction hereinafter set forth, reference being had to the accompanying drawings, forming a part of this specification, in which:—

35 Figure 1 is a central vertical sectional elevation of the invention, showing the parts thereof in normal position; Fig. 2 is a similar view showing the bucket at the instant when it is tipped and when the piston starts 40 its upward movement; Fig. 3 is a similar view, showing the piston elevated to admit of the discharge of water through the outlet; Fig. 4 is a horizontal section on the line 4—4, Fig. 1; and Fig. 5 is a partial vertical 45 transverse section on the line 5—5, Fig. 3.

Referring to said drawings, in which like designating characters distinguish like parts throughout the several views—1 indicates a body or casing which constitutes a water receptacle, 2 a cover removably mounted on said body, and 3 the inlet port through which steam and the water of condensation are forced into the receptacle under pressure. In entering through said port 3 the water strikes against a baffle 4, preferably formed integral with the casing, and is by it

deflected or directed downward toward the bottom of the receptacle. Depending within said receptacle from the under side of said cover 2 is a hanger-like support 5 to which 60 is pivotally connected lugs 6 carried by the rear end of a float or buoyant bucket 7 which normally floats in a substantially horizontal position upon a body of water retained within the trap body or receptacle 1. 65

The cover has formed thereon, or, preferably, integral therewith, a vertical cylinder 8, closed at its upper end by a bolted-on head 9, and communicating at its lower end with a vertically disposed tube 10 which depends 70 within the bucket, having its upper end threaded into the cover 2 behind the lower annular flange of a cylindrical member 11 whose upper edge is shaped to form a valve-like seat 11^a at the lower end of said cylinder 75 8. Mounted within said cylinder is a piston 12 having a reduced lower end 12^a which is beveled annularly to correspond with seat 11^a and constitutes a valve normally resting upon said seat for closing the outlet 13 to 80 the atmosphere, it being of course understood that a waste-pipe (not shown) connects with said outlet.

For guiding the piston 12 in its movements, a sleeve or stem 14 is fixed thereto 85 and is slidable through the hub 15 of a spider-like guide whose arms 16 are preferably integral with the member 11.

The piston 12 has a central bore 17 extending vertically therethrough in register 90 with the bore of said sleeve or stem 14, and slidable therein is the stem 18 of a valve 19. The lower end of said stem 18 is pivotally connected or linked to a suitable bolt 20 fixed to the bottom of the bucket. A guide member 21 of spider form is preferably provided for said valve stem 18 near the lower end of tube 10. Said valve 19 normally occupies a position closing the lower end of a bore or cored-out opening 22 provided in a 100 plug 23 which is seated centrally in the top of the head 9 and which has radially disposed ports 24 leading through the walls thereof into communication with a chamber 25 formed in said head. Said chamber communicates at one side of said head, through a passage 26, with a passage 27 formed in the cylinder wall and leading to the outlet 13, a ground joint being formed between 105 said head and said cylinder wall for preventing leakage. When the valve 19 is off its seat, communication is had between a 110

pressure chamber 28, above the piston, and the bore 22 in the plug 23 through ports 29 provided in the under side of the head 9.

The lower portion of the piston is reduced 5 in diameter, an annular shoulder thus being formed which is adapted to seat upon an integral internal annular shoulder 30 carried by the cylinder above the outlet 13. Packing rings 31 are carried by the larger upper 10 portion of the piston, as shown, and followers 32 and 33 are screwed up against said rings. The uppermost follower, 33, has formed at intervals upon its upper face a plurality of upright shoulders 33^a whereby 15 the piston is prevented from seating closely against the under side of the head 9 when elevated, as shown in Fig. 3, so as to wholly occupy the pressure chamber 28.

When the bucket occupies its normal position, as shown in Fig. 1, the valve 19 is held seated, and steam passing to the pressure chamber 28 through the constantly open passage, constituted by the bores in the sleeve or stem 14 and in the piston, in which 20 the valve stem 18 operates, exerts a pressure which holds the piston depressed with its reduced lower end upon valve seat 11^a, maintaining the outlet 13 closed. It will of course be understood that the purpose had 25 in view in forming the piston with two different diameters is to provide a greater area exposed to the pressure at the upper end of the piston than the area which is exposed to pressure in the receptacle 1. When the 30 incoming water rises to a point in the receptacle where the bucket is filled to a sufficient depth that the weight thereof overcomes the pressure holding it in normal position, said bucket is tipped by force of 35 gravity, withdrawing said valve 19 from its seat, as is shown in Fig. 2. The pressure in the chamber 28 is thus relieved, being permitted to escape, as is indicated by arrows in Fig. 2, whereupon the pressure within 40 the body of the casing or receptacle, acting upon the lower end of the piston, elevates the latter, opening the outlet 13, as shown in Fig. 3, admitting of the discharge of the water through said outlet.

50 When sufficient water has been exhausted, the bucket regains its buoyancy and resumes its normal horizontal position, seating valve 19. Pressure immediately accumulates in the pressure chamber 28 to a point where it 55 equalizes with that which, acting upon the reduced end of the piston, holds the piston elevated, and the latter drops upon the seat 11^a, closing the outlet. The downward movement of the piston is effected partially 60 through gravity and partially by the force of the accumulating pressure in said pressure chamber acting upon the greater exposed area of the piston.

The foregoing operations wherein the piston 65 ton is reciprocated, opening and closing the

outlet for the exhaust or discharge of condensations, is repeated at intervals in more or less rapid succession, the water being ejected in frequent substantially regular spurts which may be characterized as pulsations.

To provide means whereby additional weight may be conveniently applied to the free end of the bucket for lowering the buoyancy of the latter to a requisite point, a 70 tubular bore 34 is provided in the front wall of the bucket, said bore being adapted to be filled, or partially filled, with Babbitt metal. For the purpose of allowing the bucket to be further tipped than would otherwise be possible, the rear wall thereof is upwardly and rearwardly flared, as shown at 35 in Figs. 1 and 4, the curvature of the flare corresponding substantially with that of the tube 10, so that when the bucket is tipped, as 80 shown in Figs. 2 and 3, said tube will be 85 partially embraced thereby.

The lugs 6 of the bucket are mounted upon threaded pivot-pins 36 having conical points seated in sockets provided therefor in the 90 lower end of the hanger-like support 5. Lock-nuts 37 are jammed against the lugs 6, as shown in Fig. 5, for maintaining said lugs and said pins in adjusted relation. As is obvious, wear on the pins or their seats 95 may be readily compensated for by slight adjustment of said pins.

The bottom of the casing is concavely curved, as shown in Fig. 5, and is inclined downward in a forward direction, as shown 100 in Figs. 1, 2 and 3, so that sedimentary deposits may be readily drained from the receptacle through a blow-off 38 located at a suitable point in the front end of the casing.

It will be apparent that various changes 105 or alterations, within the scope of the appended claims, in the construction and arrangement of some of the parts may be resorted to without departing from the general spirit or scope of the invention.

Having thus described my invention, what I claim as new, and desire to secure by Letters Patent, is—

1. In a steam trap, a water receptacle having a removable cover, a float member in 115 said receptacle, a cylinder located above said cover, a water discharge outlet from said cylinder, a piston in said cylinder, a pressure chamber above said piston, means constantly admitting steam pressure to said 120 chamber, a plug having a passage therethrough, relief passages leading from said chamber to the passage in the plug, and a relief valve located within said chamber, said valve having operative connections with 125 said float member whereby it normally seats in the passage in the plug and holds said relief passages closed to maintain pressure in the chamber for holding the piston depressed in outlet-closing position.

2. In a steam trap, a water receptacle having a removable cover, a float member in said receptacle, a cylinder located above said cover, a water discharge outlet leading from said cylinder, a piston in said cylinder, the opposite ends of said piston having different pressure areas, a pressure chamber above said piston, a removable plug having a bore and side-opening ports therein, relief passages leading from said chamber and communicating with said bore, a relief valve in said chamber and having its stem operating through said piston, said valve being normally seated closing said passages and the bore in said plug, said stem having pivotal connection with said float member, a con-

stantly open passage for pressure from the receptacle to the pressure chamber, said chamber containing pressure, when the relief valve is closed, for maintaining the piston depressed into outlet-closing position, and said piston being adapted, upon the pressure in said chamber being relieved, to be elevated by the pressure in the receptacle to outlet-opening position.
